TORCH

Filed March 19, 1927

Inventor:
George A. Morrison,
By Drydenforth, Lee, Britton & Miles,
Attoys.

UNITED STATES PATENT OFFICE.

GEORGE A. MORRISON, OF PARK RIDGE, ILLINOIS, ASSIGNOR TO TORCHWELD EQUIPMENT COMPANY, OF CHICAGO, ILLINOIS, A CORPORATION OF DELAWARE.

TORCH.

Application filed March 19, 1927. Serial No. 176,678.

My invention relates more particularly to torches employing as the fuel, mixed gases, as for example and more especially oxygen and acetylene, and involving a so-called 5 flash-back chamber extending at a side of the mixer device in which the gases are mixed and operating to retain, during the normal operation of the torch, a body of the mixed gases for ignition in the case of flash-back to effect the extinguishment of the 10 flame in the torch substantially as disclosed in U. S. Patent No. 1,304,198 granted to Carl J. Nyquist, May 20, 1919.

It has been found in practice that it is 15 necessary, in order that the torch function to the best advantage, that leakage of the oxygen into the acetylene gas passage and leakage of the acetylene gas into the flash-back chamber be prevented inasmuch as 20 either leakage referred to is liable to result, in case of flash-back, in sustaining the flash-back resulting in the continued burning of the gas internally of the torch, it being my primary object to prevent such objectionable 25 intermixture of the gases to the end that when a flash-back occurs, the flame in the torch will become extinguished and remain extinguished until the gas mixture is ignited at the tip.

30 Referring to the accompanying drawings: Figures 1 and 1^a are views in longitudinal sectional elevation of a so-called cutting torch embodying my improvements, these views being continuations of one another. 35 Figure 2 is a view in side elevation of the mixer device of the torch; and Figure 3, an enlarged sectional view of the mixer device and the surrounding body portion of the torch, the section being taken at the line 40 3—3 on Fig. 1 and viewed in the direction of the arrows.

The torch shown comprises a handle portion 4 formed of a block 5 and a surrounding shell 6, the block 5 containing an acetylene gas passage 7 communicating with a 45 valved fitting 8 which would be connected with any suitable source of acetylene gas. The block 5 also contains a passage 9 communicating with a fitting 10 which would be connected with any suitable supply of oxygen under pressure, the acetylene gas passage 7 communicating with one end of a pipe 11 and the passage 9 communicating with a high pressure oxygen pipe 12 and a 55 low pressure oxygen pipe 13. The connec-

tions between the passage 9 and the pipes 12 and 13 and the means whereby the pipe 12 is supplied with high pressure oxygen and the pipe 13 with low-pressure oxygen is not illustrated as this forms no part of my present invention and such an arrangement and provision of parts is well known in the art. 60

The pipe 13 connects at its forward end with passage-equipped fittings 14, 15 and 16, as is well known in the art, the forward end of the fitting 16 screwing into the rear end of a socket 17 in the head or body portion, 65 18. The forward end of the socket 17, and represented at 19, opens into a passage 20 which, in turn, opens into a chamber 21 in 70 the forward end of the head and in communication with the passages 22 as usually provided in the burner tip 23 mounted in the extremity of the head 18 and through which the mixture of acetylene and low-pressure oxygen discharges for ignition at 75 the end of the tip. The high-pressure oxygen pipe 12 communicates with a passage 24 opening into a centrally disposed passage 25 in the burner tip and through which high-pressure oxygen is discharged for mixture with the intermixed acetylene and the low-pressure oxygen discharging through the 80 passages 22, in the use of the torch for cutting purposes. 85

The head 18 between the ends of the socket 17 contains a passage 26 communicating with the acetylene pipe 11, the head 18 between the passage 26 and the forward extremity of the socket 17 containing a circular tapering seat 27. The socket 17 is threaded rearwardly from the passage 26 as 90 represented at 28 and at the rear end of this threaded portion presents an annular seat 29. 95

The mixer device by which the low-pressure oxygen and the acetylene gas are mixed for discharge into the passage 20 and thence into the burner tip is represented at 30 and is secured in the socket 17 by the engagement of its threaded portion 31 with the threads 28. The forward extremity of the mixer 100 30 is of such external diameter and is of such length that when positioned in the body portion 18 it extends in spaced relation to the socket 17 as shown thereby affording a flash-back chamber 32 in which, during the normal operation of the torch, a combustible body composed of acetylene and oxygen is maintained, this flash-back chamber being in communication with the longi- 105 110

tudinal bore 33 of the mixer device through a passage 34 in the latter and inclining in the direction of the flow of gas through the mixer device. The mixer device is formed 5 with an annular beveled shoulder 35 adapted to seat against the shoulder 27 and with an annular shoulder 36 adapted to engage the seat 29, the wall of the mixer device between the shoulder 35 and the threaded portion 30 10 thereof being spaced from the wall of the socket 17 to provide a chamber 37 in communication with the acetylene gas passage 26, the chamber 37 being in communication with the central passage 33 of the mixer device through forwardly inclined radial passages 38 in the mixer device.

The internal contour of the socket 17 and the external contour of the mixer device 30 are such that when the mixer device 30 20 is screwed into the body 18 to the position shown in Fig. 1, the shoulders 35 and 36 will forcibly press against the seats 27 and 29 and form gas-tight joints one between the acetylene gas passage 26 and the low-pressure oxygen passage and the other between this acetylene gas passage and the flash-back chamber 32, thereby effectually preventing leaking of the oxygen into the acetylene gas passage 26 and the leakage 25 of acetylene from this passage into the flash-back chamber 32 and thus preventing the sustaining of the flame in the torch in the event of flash-back which ignites the charge in the flash-back chamber 32 and produces 30 extinguishment of the entire flame in the torch.

In the manufacture of the torches, the mixer device is formed to cause the distance between its shoulders 35 and 36 to be slightly greater, as for example about $3/1000$ of an inch, than the distance between the seats 27 and 28, which ensures the production of the desired gas-tight joints above referred to, it being understood that by reason of the provision of the seats 27 and 35 as shown, and the forming of the body 18 and the mixer 31 of brass and bronze, respectively, which are the materials usually used for these parts in torches as commonly provided, the metal at this forward joint becomes deformed in the drawing of the shoulder 36 into tight engagement with the seat 29.

While I have illustrated and described a 55 particular construction embodying my invention, I do not wish to be understood as intending to limit it thereto, as the same may be variously modified and altered without departing from the spirit of my invention.

What I claim as new, and desire to secure by Letters Patent, is:

1. A gas-torch comprising a body-portion

containing passages for gases, respectively, a mixer device in said body portion and in communication at its rear end with one of said passages and intermediate its ends with the other of said passages, a flash-back chamber at the side of said mixer device in front of said last-referred-to passage, and seats in said body portion between said flash-back chamber and said last-referred-to passage and between said passages, respectively, and facing in a direction away from said flash-back chamber, and engaged by portions 65 of said mixer-device to form gas-tight joints. 70

2. A gas-torch comprising a body portion containing passages for gases, respectively, a mixer device in said body portion and in communication at its rear end with one of said passages and intermediate its ends with the other of said passages, a flash-back chamber at the side of said mixer device in front of said last-referred-to passage, and seats in said body portion between said flash-back chamber and said last-referred-to passage and between said passages, respectively, and facing in a direction away from said flash-back chamber, and engaged by portions 80 of said mixer-device to form gas-tight joints. 85

3. A gas-torch comprising a body-portion containing passages for gases, respectively, a one-piece mixer device screwed into said body portion and in communication at its rear end with one of said passages and between its forward end and its threaded portion with the other of said passages, a flash-back chamber at the side of said mixer device in front of said last-referred-to passage, and seats in said body portion between said flash-back chamber and said last-referred-to passage and between said passages, respectively, and facing in a direction away from said chamber and engaged by portions 95 of said mixer-device to form gas-tight joints. 100

4. A gas-torch, comprising a body-portion containing passages for gases, respectively, a mixer device in said body portion and in communication at its rear end with one of said passages and intermediate its ends with the other of said passages, a flash-back chamber at the side of said mixer device in front 110 of said last-referred-to passages, and seats of different diameters in said body portion between said flash-back chamber and said last-referred-to passage and between said 115 passages, respectively, and facing in a direction away from said chamber and engaged by portions of said mixer-device to form gas-tight joints, the smaller of said seats being innermost. 120

GEORGE A. MORRISON.
